METHOD OF AND APPARATUS FOR GAS BLAST CIRCUIT INTERRUPTION

Filed Sept. 24, 1929

UNITED STATES PATENT OFFICE

SIGWART RUPPEL, OF FRANKFORT-ON-THE-MAIN, GERMANY

METHOD OF AND APPARATUS FOR GAS BLAST CIRCUIT INTERRUPTION

Application filed September 24, 1929, Serial No. 394,348, and in Germany October 2, 1928.

This invention relates to the control of compressed gas or fluid-blast switches and has for its object the provision of an improved method and apparatus for controlling switches of the aforesaid character.

The control of circuit interrupters of the fluid-blast type, as gas-blast switches, depends on a number of factors including the interrupting capacity of the switch, the design of the contact structure and switch parts, and the character of the gas blast. In general, it may be said that a comparatively limited separation of the switch contacts between which the blast is directed is effective to cause interruption of the circuit. Reestablishment of arcing may be prevented by interposing additional dielectric in the circuit, as by further lengthening of the arc gap or by the opening of so-called disconnecting switches connected in series in the circuit. In the case where separate disconnecting switches are dispensed with, the additional dielectric may be inserted by lengthening the switch opening stroke.

The current interrupting action of the blast is most effective when the blast bears a certain relationship to the gap traversed by the blast and the current to be interrupted. In general, the gap is comparatively small, as of the order of a few millimeters when gas at high pressure is used. The contacts, which are separated abruptly, therefore have interposed between the same a compressed gas layer which is sufficient to interrupt the current and to prevent reestablishment of arcing. The above relationship, however, is not constant for a given circuit interrupter and may vary under different operating conditions. There is, therefore, a range within which the gap may vary coincident with the most favorable interrupting conditions.

In accordance with my invention the switch opening movement is effected so that the zone or range within which the most favorable blast interrupting action may be had is traversed slowly and the circuit is interrupted in the most effective manner. Further, in accordance with my invention, the switch opening movement is at first effected rapidly and thereafter is retarded

within the most effective blast zone, the completion of the switch opening movement being at increased speed.

My invention will be more fully set forth in the following description referring to the accompanying drawing, and the features of novelty which characterize my invention will be pointed out with particularity in the claims annexed to and forming a part of this specification.

Referring to the drawing, Fig. 1 is a partly diagrammatic illustration of operating mechanism for carrying out the method embodying my invention; Fig. 2 shows another arrangement of operating mechanism, and Fig. 3 is a sectional view of pneumatic operating means for carrying out the above method.

As stated in the general description, it is preferable under certain conditions to alter the speed of the switch part which is moved, during the switching out movement. This can take place in different ways as described by way of example in the following figures.

In one such arrangement there is provided a drive shaft or spindle having mounted thereon spur wheels of different sector diameters arranged to engage alternatively toothed wheels or gears mounted on the switch actuating shaft so that the speed of rotation of the switch actuating shaft may be varied during the switching out movement with uniform speed of rotation of the drive shaft. In this arrangement, the aforesaid wheels and gears are mounted on the respective shafts as by means of lock cones, or any suitable free-wheeling arrangement, arranged so that upon rotation of the drive shaft in the opposite direction for effecting closing of the switch the shafts are coupled by gear wheels transmitting uniform closing movement to the switch. Fig. 1 shows an arrangement for operating a switch 10 in which the actuating means or drive engages the lever 47 of the driving shaft 45. On the shaft 45 are coupled, through suitable one-way drives or free-wheeling arrangements, the spur-wheels 49 and 51 for one direction of rotation, and the toothed wheel 54 for the other direction of rotation. Free-wheeling arrangements of

a well known type are diagrammatically illustrated at 49', 51' and 54' for the wheels 49, 51 and 54 respectively. On the switch spindle 46, the lever 48 of which operates the switch 10, are fitted the spur-wheels 50, 52 and 53. While the wheels 53 and 54 which effect the switching in operation are continuously in engagement, the toothed wheel 52 is provided with teeth over only a part of its circumference as diagrammatically illustrated. The same applies to the toothed wheel 49 on the spindle 45. The switched-in or closed circuit position is shown in Fig. 1.

In this position the movable rod contact 11 of the switch 10 is in engagement with a stationary nozzle-like contact 12 substantially at the restricted portion of said contact. The rod contact is suitably guided for longitudinal reciprocal movement within a gas chamber 13 which is formed by an insulating switch casing 14. The gas chamber 13 is in communication with the nozzle contact 12 and a gas supply conduit 15 so that upon opening of the switch contacts gas under pressure may be directed into the gas chamber so as to exhaust through the nozzle contact 12 and extinguish arcing between the contacts in the manner previously described. The switch actuating lever 48 is suitably connected to the lower end of the contact rod 11 as by a pin and slot connection 48', it being understood that the operative connection between the opening mechanism and the switch is diagrammatic and without reference to the correct proportioning of the corresponding movements of said mechanism and switch.

On the switching out, the spindle 45 is rotated clockwise, and through the wheel 49 rotates the wheel 50 of the spindle 46 with it. The circumferential speed of the spindle 46 is here in proportion to the arc radii greater than that of the spindle 45. The contact separating speed for the initial opening movement is diagrammatically indicated in Fig. 1 is therefore high. In the further course of the switch opening movement, the wheels 49 and 50 come out of engagement, and in their place the wheel 52 engages the wheel 51 which causes a reduction of the circumferential speed of the spindle 46 in proportion to the radii, which is equivalent to a slowing down of the switch opening movement. This opening movement is arranged so as to be in the most favorable blast zone for the reasons above given and is likewise indicated in the drawing. In the latter part of the switching out movement, the wheel 49 again engages with the wheel 50, while the wheel 52 is out of engagement with the wheel 51. The circumferential speed therefore again increases, and the latter or final part of the switching out movement indicated in the drawing is completed at greater speed.

During the switching out process, the wheel 54 driven by the wheel 53 runs loose as indi-

cated. On the switching in the spindle 46 is moved through the wheels 54 and 53, while the wheels 49 and 51 run idly. The switching in process is therefore completed without reduction or alteration of speed.

It will be apparent that the above arrangement may be modified so as to include cams suitably designed so as to effect reduction of the switch opening speed throughout the range of the most effective blast action.

Another arrangement includes an elastic intermediate member, as a spring for example, included in the coupling between the driving and the switch actuating shafts. In this arrangement the switch actuating shaft is first rotated at high speed by the driving shaft until the former abuts a stop member. There is a dwell in the opening movement of the switch shaft at this point, the stop member being subsequently released by continued actuation of the driving shaft so that the switch opening movement is completed. During the aforesaid dwell the driving shaft has stored up energy in the intermediate member of the coupling which is effective, after the release of said stop, to cause final opening movement of the switch at high speed.

In Fig. 2 the switch spindle 46 is actuated by the driving spindle 45, through the spring 58, which together with the slotted rocking link 57 is suspended at the point 64 of the lever 55 and the point 65 of the lever 66. The drive of the switch piece 60 is effected by the lever 55 through the connecting link 59. On switching out or counter-clockwise movement of lever 66 the lever 55 is rotated in the same direction by the spring 58 until the stop 56 rests on the stop lever 61. The stop lever 61 is carried loosely on the spindle 45 and is held by the spring 63 in the correct position. It has, furthermore, a stop 62. After the lever 55 has been prevented from further movement by the stop 56, the spring 58 is tensioned so that when the lever 66 has carried the stop lever 61 along with it at 62, the lever 55 now released, is thereby brought suddenly into the end position of the switching out movement. In the switching-in movement the lever 66 carries the lever 55 directly with it through the link 57. The switch piece therefore comes to a stop during the switching out movement after a short time, then moves with increasing speed into the end position.

The aforesaid arrangements for effecting variable speed opening of the switch by mechanical means may be used for practically every type of fluid-blast switch wherein positive separation of the contacts is effected. In certain types of pneumatic drives including a piston for effecting closing and opening of the switch by gas pressure a special type of pneumatic control may be used to advantage. For example in a pneumatic pis-

ton drive, the pressure difference at opposite sides of the piston may be so controlled, as by by-passes or the like, that the initial movement of the piston takes place quickly, then is retarded throughout the most effective blast range and finally is accelerated to complete the switching out. By arranging a one-way valve within a by-pass in the piston cylinder the desired variation in the switch opening movement may be obtained whereas the switch closing movement may be effected at substantially constant speed.

In Fig. 3 a pneumatic arrangement for effecting variable opening speed of the switch is shown comprising a driving cylinder 5 of a compressed gas gear, in which the piston 6 moves with the switch actuating or piston rod 33. The pipe 67 is in communication with the compressed gas supply for switching out, as is the pipe 72 for switching in. Furthermore, the circulating or by-pass pipe 68 is arranged on the cylinder, the check valve 69 being mounted within the same.

The switching out procedure takes place as follows: Compressed gas flows through the pipe 67 into the cylinder behind the piston 6 which moves with great speed towards the right. By means of the venting pipe 70 with adjusting cock 71 or equivalent means the right-hand side of the cylinder is at low pressure. For the purpose of retarding the opening speed of the switch in the manner previously described, the piston 6 is bypassed after an initial high speed opening movement so that the opening force is suddenly reduced. The by-passing takes place, however, only within the range of the most effective blast interrupting action, beyond which the full opening force is again applied. After a certain and adjustable distance, the piston uncovers the gas inlet to the pipe 68 and the compressed gas is admitted by the valve 69 to the right-hand side of the cylinder in front of the piston. The piston speed is rapidly reduced in accordance with the small difference of pressure before and behind the piston. As, however, the right-hand side of the piston has been exhausted through the adjustable opening 70, the piston moves slowly forward until it closes the compressed gas outlet of pipe 68 so that it is no longer by-passed, and then by the increase of the pressure difference the switch movement to the end is quickly made. The check valve 69 prevents the switching-in compressed gas in front of the piston from flowing away, the switching in process is therefore completed with the desired alteration of speed. As the travel of the piston may be made equal to that of the switch, the switch piece is here also moved with variable speed during the switching out operation and uniform speed during the switching in process.

It should be understood that my invention is not limited to specific details of construc-

tion and arrangement thereof herein illustrated, and that changes and modifications may occur to one skilled in the art without departing from the spirit of my invention.

What I claim and desire to secure by Letters Patent of the United States of America is:—

1. The method of operating a circuit interrupter of the fluid-blast type which comprises effecting opening movement of the circuit interrupter at an initially high rate and reducing the rate of contact separation through the range within which the interrupting action of the blast is most effective.

2. The method of operating a circuit interrupter of the gas-blast type which comprises effecting quick initial switch opening movement of the circuit interrupter, retarding the speed of contact separation and continuing the separation at a reduced rate through the range within which the interrupting action of the blast is most effective, and resuming said opening movement at a higher rate.

3. Operating mechanism for circuit interrupters of the gas-blast type including a switch actuating member, comprising means effecting high speed initial opening movement of said actuating member, means retarding said member and causing a lower rate of opening movement within a predetermined range in the opening stroke, and means effecting continued opening movement of said member at a higher rate.

4. Operating means for a circuit breaker of the gas blast type comprising a piston for effecting separation of the circuit breaker electrodes, a cylinder within which said piston operates, means for admitting gas under pressure at one end of said cylinder for effecting switch closing movement of said piston, means for admitting gas under pressure at the other end of said cylinder for effecting switch opening movement of said piston, and means for varying the opening speed of said piston including a by-pass for said piston in said cylinder, and a valve for controlling flow of gas through said by-pass so that said piston is checked in its opening movement.

5. Operating mechanism for a circuit breaker of the gas blast type comprising a piston for causing separation of the switch electrodes at variable speed, a cylinder within which said piston operates, means for admitting gas under pressure at one end of said cylinder for effecting circuit closing movement of said piston, an adjustable vent at the same end of said piston, means for admitting gas under pressure at the other end of said cylinder for effecting circuit opening movement of said piston, a by-pass for said piston in said cylinder including a valve normally biased to prevent flow of gas through said by-pass during circuit closing.

movement of said piston, said piston being checked in its circuit opening movement by said by-pass and said adjustable vent causing continued opening movement of said piston 5 until said piston has covered the exhaust end of said by-pass whereby said opening movement is resumed at normal speed.

In testimony whereof I affix my signature.
SIGWART RUPPEL.
